US0D1071183S

(12) **United States Design Patent** (10) **Patent No.:** **US D1,071,183 S**
(45) **Date of Patent:** **** Apr. 15, 2025**

(54) **COVER FOR URINE CUP**

(71) Applicant: **Zhejiang Orient Gene Biotech Co., Ltd**, Zhejiang (CN)

(72) Inventors: **Ying Zhang**, Zhejiang (CN); **Jianqiu Fang**, Zhejiang (CN)

(73) Assignee: **ZHEJIANG ORIENT GENE BIOTECH CO., LTD**, Zhejiang (CN)

(**) Term: **15 Years**

(21) Appl. No.: **29/858,749**

(22) Filed: **Nov. 3, 2022**

(30) **Foreign Application Priority Data**

Aug. 12, 2022 (CN) 202230525225.4
(51) **LOC (15) Cl.** **24-04**
(52) **U.S. Cl.**
USPC **D24/122**

(57) **CLAIM**

The ornamental design for a cover for urine cup as shown and described.

DESCRIPTION

FIG. 1 is a top, front perspective view of a cover for urine cup showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear, bottom perspective view thereof.

The broken lines illustrate portions of the cover for urine cup that form no part of the claimed design.

1 Claim, 8 Drawing Sheets
